FRED W. A. TECHMER, OF LA CROSSE, WISCONSIN.

FOLDING TABLE.

1,368,666.

Specification of Letters Patent. Patented Feb. 15, 1921.

Application filed May 5, 1920. Serial No. 378,977.

To all whom it may concern:

Be it known that I, FRED W. A. TECHMER, a citizen of the United States, and a resident of La Crosse, in the county of La Crosse and State of Wisconsin, have invented certain new and useful Improvements in Folding Tables, of which the following is a full, clear, and exact description.

The invention relates to folding tables.

10 One object of the invention is to provide a folding table having legs pivotally connected thereto in such manner that when they are in operative position they will firmly hold and support the table.

15 Another object of the invention is to provide an improved folding table.

The invention consists in the several novel features hereinafter set forth and more particularly defined by claims at the 20 conclusion hereof.

In the drawings: Figure 1 is a perspective showing the legs of the table folded under the table top. Fig. 2 is a perspective of one of the legs in locked position. 25 Fig. 3 is a section through the table top showing one of the legs in operative position. Fig. 4 is a detail of the lock for the lower end of one of the braces. Fig. 5 is a detail perspective of one of the brackets in 30 which the legs are pivoted. Fig. 6 is a perspective of a portion of the table in folded position.

The table comprises a top which is formed of sections 7 and 8, each of which has cleats 35 9 secured to its underside and adjacent its ends. Hinges 10 pivotally connect the cleats and are provided to permit the table-top sections to be folded together for convenience in storage. A suitable latch 11 is 40 adapted to lock the top-section in extended position when the table is unfolded for use. Legs 12 are pivotally connected to the top sections so they can be folded thereunder, as illustrated in Fig. 1, or into operative position, as shown in Fig. 2.

Brackets 14 are provided for connecting the upper ends of the legs to the top and are alike in construction. Each bracket 14 comprises parallel side walls 15 and cross-walls 50 16 which close one end of the bracket, the other end being open to permit the leg to pass into the bracket and between the side-walls 15. The cross-wall 16 abuts against the inner side of a cleat 9 so that the bracket 55 will be snugly positioned in the corner formed by the top and the cleat. Tongues

17 project laterally from the upper edges of the side walls 15 for screws or nails to attach the bracket to the underside of the table top and a tongue 18 extends outwardly 60 and laterally from wall 16 to fit against the underside of a cleat, for a screw to secure the bracket to the cleat. The side and end walls and lugs of the bracket 14 are all integrally formed and are of such construction 65 that the bracket can be formed of sheet metal and when secured to the top and the cleat will provide a firm and rigid bracket for the leg.

The upper end of each leg fits between 70 the walls 15 and 16 of one of the brackets 14 and a bolt 24 extends through the side-walls 15 of the bracket and the leg to pivotally connect the leg to the table. The leg is free to swing through the open side of the 75 bracket into folded position against the underside of one of the table-sections.

Each leg is adapted to be locked in operative position by a combined brace and lock which is formed of a rod having a pintle 25 80 on its upper end pivotally held in an ear 26 on a plate 27 which is secured to the underside of one of the table sections, an arm 28 disposed to bear against the underside of the top section, a brace portion 29, and a hook-terminal 30. A sheet-metal corner bracket 31 is extended to fit against two of the sides of a leg 12, is secured thereto by screws 32 and is provided with an angular portion 33 having an elongated slot 34 for guiding the 90 lower portion of the brace-member 29 and an inclined portion 35 formed with a hole 36 to receive the hook 30 of the brace. The brace-member is resilient and the arm 28 is formed so that it will bear against the 95 underside of the table-top and yieldingly press the hook 30 into the hole 36 and thus cause the brace to be locked in position to hold the leg at right angles to the table-top as shown in Fig. 4. When the leg is locked 100 and it is desired to release it for folding, the operator will spring the brace into position shown in dotted lines in Fig. 4 and then swing the leg toward the table-top, the brace passing through the slot 34 during the folding operation. A snap-hook 40 on the cleat 9 of one top-section is adapted to enter a slot 41 in a plate 42 secured to the contiguous cleat on the other section to hold the 105 table in folded position. When the table is 110 to be unfolded, it is only necessary to release hook 40, then swing the top-section apart

and swing the legs away from the table top. As the inclined portions 35 of the brackets 31 engage the hooks 30, they will spring the brace-members and guide the hooks into 5 holes 36 and thus automatically lock the legs in operative position. A characteristic of the arms 28 for forcing braces into locked position is that, as the braces are swung into folded position adjacent the top, the arms 28 10 will be swung away from the top to render them inoperative and permit the legs to be folded unretarded by the pressure produced by the braces.

The invention is not to be understood as 15 restricted to the details set forth, since these may be modified within the scope of the appended claims, without departing from the spirit and scope of the invention.

Having thus described the invention, what 20 I claim as new and desire to secure by Letters Patent, is:

1. A folding table comprising the combination of a table-top, a cleat secured to the underside of said top, a bracket having integral side-walls, a cross-wall connecting said 25 side walls, and laterally projecting lugs integral with the bracket for attachment to the underside of the top and cleat respectively, a supporting leg having its upper end 30 formed to pass and be held between said walls, and a hinge pin extending centrally through the leg and the side walls of the bracket.

2. A folding table comprising the combination of a table-top, a cleat secured to the underside of said top, a bracket having integral side-walls and a connecting end-wall between the side walls, laterally projecting lugs integral with the bracket for attachment 35 to the top, and a lug integral with and at the lower end of said connecting wall to underlie and for attachment to said cleat, a leg having its upper end formed to pass and be held between said walls, and a hinge pin 40 extending centrally through the upper por-

tion of the leg and the side walls of the bracket.

3. A folding table comprising the combination of a top, legs having their upper ends pivotally connected to the top, resilient 50 braces pivotally connected to the top, devices on the legs with which the lower ends of the braces are adapted to interlock to secure the legs in operative position, the braces being provided with means for forcing them 55 into locking engagement with said devices, said means being movable with the braces so as to be inoperative to force them into locking position when the legs are in folded position.

4. A folding table comprising the combination of a top, legs having their upper ends pivotally connected to the top, resilient 60 braces pivotally connected to the top, devices on the legs with which the lower ends of the 65 braces are adapted to interlock to secure the legs in operative position, the braces being provided with integral arms adapted to yieldingly force the braces into locked engagement with said devices.

5. A folding table comprising the combination of a top, legs having their upper ends pivotally connected to the top, resilient 70 braces pivotally connected to the top, brackets on and projecting from the sides of the 75 legs, having guide-slots for the braces, hooks on the braces the brackets having means to lock the hooks, and means for yieldingly forcing the hooks into locked position.

6. A folding table comprising the combination of a top, legs having their upper ends pivotally connected to the top, resilient 80 braces pivotally connected to the top, brackets on the legs having guide-slots for the braces, hooks on the braces the brackets having means to lock the hooks, integral arms 85 on the braces adapted to force the hooks into the locking means, and guide-means for the hooks on the brackets.

FRED W. A. TECHMER.
